Filed Dec. 14, 1966, Ser. No. 601,711
16 Claims. (Cl. 57—58.36)

ABSTRACT OF THE DISCLOSURE

A method and mechanism whereby a strand is fed at a controlled predetermined rate either into or out of a loop or balloon rotating at a predetermined speed at a strand twisting and/or plying spindle. The strand is continuously wound upon and unwound from a capstan disposed coaxially of the balloon by the rotation of the balloon. The capstan is rotated about its axis at a predetermined speed relative to the balloon. Direction and speed of feeding of the strand are predetermined, with a given direction of winding of the strand about the capstan, by the direction and speed of rotation of the capstan relative to the balloon.

This application is a continuation-in-part of my applications Ser. No. 531,914, filed Mar. 4, 1966, now abandoned; Ser. No. 584,288, filed Aug. 15, 1966, now abandoned; Ser. No. 598,578, filed Oct. 31, 1966 and Ser. No. 600,617, filed Dec. 9, 1966.

In my prior applications Ser. Nos. 584,288 and 600,617, I have disclosed and claimed strand twisting apparatus of the strand-wrapping type wherein the strand in a rotating loop or balloon is engaged and fed forward at a predetermined speed by a driven capstan which rotates as a whole with such strand as the latter rotates about its axis. Such strand feeding mechanism, although satisfactory, is somewhat complicated, and requires that a substantial amount of eccentrically distributed weight (the driven capstan and at least a part of its drive train) be added to a flyer, whether the flyer is the main, loop or balloon generating flyer or an auxiliary flyer. Still more weight must, as a consequence, be added to the flyer in order to bring it into dynamic balance.

In accordance with the present invention, the feeding of the strand in the rotating loop or balloon is accomplished without adding appreciably to the weight of the flyer associated with the strand feeding capstan. Such result is accomplished by disposing the capstan, in the form of a rotatable capstan roll, coaxially of the rotating loop or balloon, and mounting it on a support mounted separately from the flyer. The capstan roll and flyer are mounted for independent rotation about their axes, the flyer being driven at the same speed and direction as the loop. Guides on the flyer lead the strand onto the surface of the capstan roll and away from the capstan roll. Preferably the strand is thus led in runs extending in directions generally radially of the capstan roll. The strand is wound in substantially non-slipping relationship upon the capstan roll in such direction that the rotation of such runs of the strand about the capstan roll, taken with the rotation of the capstan roll, to be described, feeds the strand in the desired direction. In order to bring the rate of feeding of the strand to the required value, the capstan roll is rotated at such speed and in such direction that the algebraic sum or resultant of such two strand feeding effects: (1) the rotation of the flyer and thus of the runs of the strand approaching and leaving the capstan roll, and (2) the rotation of the capstan roll about its axis, yields the desired strand feeding effect.

The above and further objects and novel features of the invention will more fully appear from the following description when the same is read in connection with the

2

accompanying drawings. It is to be expressly understood, however, that the drawings are for the purpose of illustration only, and are not intended as a definition of the limits of the invention.

5 In the drawings, wherein like reference characters refer to like parts throughout the several views,

FIG. 1 is a schematic view in perspective illustrating a plying apparatus in accordance with an illustrative embodiment of the invention; and

10 FIG. 2 is a view in vertical axial section through the auxiliary flyer of the plying apparatus of FIG. 1 and showing the constant speed capstan, and the driving means therefor, for feeding the outer, ballooned singles strand to the plying point, certain of the parts being shown in elevation.

15 Turning now to the drawings, the illustrative embodiment of plying spindle, shown in FIGS. 1 and 2, is generally designated by the reference character 10. Such spindle is provided with an outer singles strand *a* from an externally mounted yarn package 11, strand *a* passing

20 through a guiding and tensioning arrangement 12 and passing into the lower end of a hollow main spindle shaft 14, as shown. Such shaft 14 may be driven by an electric motor (not shown) through the medium of a "timing" belt 15. After rising through the bore in the spindle shaft 14, strand *a* emerges through a radially directed opening 16 in a storage wheel 17 affixed to the shaft 14, and is then wound to a varying degree in the operation of the spindle about such strand storage wheel. After leaving the storage wheel 17, the strand *a* passes into a balloon or rotating loop 19 which is formed coaxial of the spindle 14 and surrounds a stationary housing 20 and the inner package 21 of the strand *b* contained therein. In the embodiment disclosed, the housing 20, the inner package 21, and the

35 package holder, not specifically shown, are mounted by bearings on the upper end of shaft 14, and such parts are held from rotation by eccentrically weighting the package holder, as is conventional in the art. In the following description and claims the term "rotating loop" means the portion of strand *a* which rotates about its axis and which extends from a first zone thereof lying on or substantially on such axis to the zone thereof at its final passage into or out of the loop along or substantially along such axis. The terms "rotating loop proper" or "loop proper" are

40 meant to include only that portion of strand *a* which rotates about its axis and which extends from a first zone thereof lying on or substantially on such axis to the zone thereof at its next passage to or adjacent to such axis.

45 Strand *b* passes upwardly from the package 21 through a tension means 22 mounted on housing 20, means 22 imposing a substantially constant retarding tension on strand *b*. Strand *b* then travels vertically upwardly substantially along the axis of the spindle shaft 14 to meet the singles strand *a* at a plying point P, as shown in FIG. 2. Strand *a*

50 adjacent the top of its rotating loop or balloon 19 engages a capstan roll 45, about which the strand *a* passes in multiple wraps with substantially non-slipping relationship therewith, capstan roll 45 being disposed relative to an auxiliary flyer, generally designated 24, in a manner to

55 be explained. The strand *a* is forwarded at constant speed by capstan roll 45 to the plying point, the tension in the portion of strand *a* between such capstan roll 45 and the plying point P being independent of the tension of the strand *a* in balloon 19, since the capstan roll 45 serves to

60 isolate the tension in the balloon 19 from the tension in such strand portion.

65 The plied strand or cord *c* is withdrawn under tension from the plying point P by a take-up capstan 26 which has two spaced parallel capstan rolls 27 around which the cord travels in multiple wraps in substantially non-slipping relationship. In the embodiment shown, capstan

26 is driven at constant speed, such drive being by way of bevel gear sets 29, one gear of each such set being fixed to a driving shaft 30. Shaft 30 in turn is shown as being driven by a constant speed, synchronous motor 34 through the medium of a pinion 32 on the motor shaft and a large gear 31 on shaft 30. It will be understood that the capstan 26 may be driven in other manners, as by being driven by and synchronously with the spindle 14.

The illustrative embodiment of capstan and flyer arrangement is more particularly shown in FIG. 2. As there shown, a tube or hollow spindle 36 is mounted coaxial of the spindle shaft 14 exteriorly of the balloon or loop 19 by means of a fixed supporting member 25 which may be a part of the frame of the apparatus. The lower inner edge of the bore through the spindle 36 is flared as shown at 37, whereby to serve as a guide for the plied strand or cord *c*. The auxiliary flyer 24 has a hollow cup-shaped body 40 of generally conical shape, such body having a thickened central flange portion 44 at its upper, smaller diameter end. The body of flyer 24 may be made, for example, of a light strong metal such as high strength aluminum alloy. Since the flyer body is subjected to low stresses other than those arising from its rotation at high speed, however, it can as an alternative be made of strong, tough plastic material reinforced, for example, by glass fibers extending peripherally of the body. Although an auxiliary flyer with a continuous body, as shown, is preferred, it may be replaced, if desired, by generally radially disposed braced rod-like members providing support for the strand guides 46, 47, 49, and 50, to be described.

The flyer 24 is supported for rotation about its axis, coaxial with spindle 14, on an outer bearing 41, an upstanding annular member 42 integral with flange 44 of body 40 serving as the inner race of such bearing. The outer race 41 of the bearing is fixed to support 25. In the embodiment shown, the spindle or hollow shaft 36 is rotatably mounted in the flange 44 of the auxiliary flyer by means of a second, inner bearing 39 between parts 36 and 44. It will thus be seen that the spindle 36 and the auxiliary flyer body 40 are mounted for independent rotation with respect to each other.

Affixed to the spindle 36 coaxially thereof within the body of flyer 24 and adjacent the lower end of the spindle 36 is a capstan roll 45 which in the construction shown is provided with a concave or dished peripheral surface 48. The body 40 of flyer 24 serves to support vertically aligned lower and upper guides 46 and 47, which lead the strand *a* from the upper end of the ballooning portion of the rotating loop of such strand upwardly to generally the vertical center of surface 48 of capstan roll 45. Additionally, the guide 46 serves to drive the auxiliary flyer for rotation about its axis by and in synchronism with the ballooning strand *a*. Guides 46 and 47, as well as guides 49 and 50, to be described, are shown as being pigtail guides having their shanks screw threaded into the body 40 of the flyer 24. Such guides may, however, be replaced by other guides or guiding means, such as rollers mounted on the body 40 on anti-friction bearings.

After leaving guide 47, the strand *a* passes to the capstan roll 45 to be wrapped a plurality of times (3 or 4, for example) around the surface 48 of roll 45 so as to have at least substantially non-slipping engagement with such surface. The strand *a* then leaves the capstan roll 45 and passes to guide 49 which is secured to the body 40 of the auxiliary flyer 24. Guide 49 is shown as being disposed in substantially the same vertical axial plane as guide 47, and at substantially the same horizontal level as guide 47. It will be understood that the angular displacement of guides 47 and 49 about the axis of the flyer body 40 may be varied widely, consistent with avoiding interference between the various runs of the strands within the body of the flyer 24. The guides 47 and 49 are shown disposed at slightly different heights, to insure that the wraps of the strand *a* on the surface 48 of capstan roll 45 will lie side

by side from their entrance upon until they leave such surface.

The action of the strand feeding apparatus will be better understood by the following facts:

5 (1) To feed the strand *a*, the capstan roll must rotate relative to the runs of the strand (1) approaching and (2) leaving it.

10 (2) With a given direction of wrap of the strand about the capstan roll, the strand is fed in one direction by rotating the capstan roll in a first direction A relative to runs (1) and (2), and in the second, reverse direction B by rotating the capstan roll in the other direction relative to runs (1) and (2).

15 (3) Reversal of the direction of wrap of the strand about the capstan roll will reverse the respective direction of feed of the strand given by capstan roll rotations A and B.

20 (4) Runs (1) and (2) of the strand *a* rotate in the same direction and at the same speed as the loop.

(5) To obtain rotation of the capstan roll relative to runs (1) and (2), the capstan roll must rotate at a speed different from the speed of rotation of the loop.

25 (6) For strand feeding speeds within the range useful in the illustrative ply-wrapping method and apparatus, the speed difference in (5), above, is relatively small, and depends upon the effective diameter of the surface 48 of the capstan roll.

30 (7) The strand feeding speed is proportional to the algebraic sum of the strand feeding effects of the rotation of the loop and of the capstan roll.

(8) The capstan roll, for strand speeds useful in the illustrative apparatus, rotates in the same direction as the loop.

35 (9) With a given direction of winding of the strand on the capstan, when the speed of rotation of the capstan roll is lower than the speed of rotation of the loop, the strand is fed in one direction, and when the speed of rotation of the capstan roll is higher than the speed of rotation of the loop, the strand is fed in the other direction.

40 (10) It is ordinarily preferred that, with constant speed strand feeding apparatus in accordance with the invention, the capstan roll be driven at a speed lower than that of the loop. The reasons for this are, among others, economy of power and the decrease in the wearing of parts.

45 It will be seen that the generally radial runs of strand *a* (1) between guide 47 and capstan roll 45 and (2) between capstan roll 45 and guide 49 rotates at the same speed, the speed of rotation of the balloon and flyer 24, about the axis of the capstan roll. Thus (a) if the capstan roll 45 were freely rotatable with such runs of strand *a* the capstan roll 45 would have no feeding action upon strand *a*, since there would then be no rotation of runs (1) and (2) of strand *a* relative to the capstan roll. The same result would, of course, be obtained if the capstan roll 45 were secured to the flyer to rotate at the same speed and in the same direction as the flyer. If, however, (b) the capstan roll 45 were held non-rotatable in space, 55 assuming a proper direction of winding of the strand on roll 45, the strand *a* would be fed forwardly in the proper direction but at much too high a speed for the present purpose, the speed of feeding of strand *a* then being such that a length of strand *a* equal to the effective circumference of capstan roll 45 would pass such roll on each revolution of the flyer.

60 In order that the capstan roll shall feed strand *a* forward at the proper speed, it is necessary that the capstan roll 45 rotate in the same direction as the flyer, but at a predetermined speed slightly different from that of the flyer. In the illustrative embodiment the capstan roll 45 rotates at a speed which is slightly less than the speed of the flyer. The result is that the capstan roll 45 rotates in such direction relative to the flyer as to forward strand *a* at the desired speed. This will perhaps be better under-

stood by considering FIG. 2, wherein the flyer 24 is indicated as rotating in a clockwise direction when viewed from below, and the runs (1) and (2) of strand *a* initially engage and leave, respectively, the portion of the periphery 48 of the capstan roll 45 which is remote from the reader in FIG. 2. If the flyer 24 were imagined as being stationary, under an assumed static condition, to feed the strand *a* in the desired direction of from left to right in FIG. 2, the capstan roll 45 would then have to be turned counterclockwise. The same strand feeding result is obtained, under actual, dynamic operating conditions, with the flyer 24 turning in a clockwise (from below) direction, and capstan roll 45 turning in the same direction, but at a slightly slower speed. Here again, the capstan roll 45 turns in a counterclockwise direction relative to the flyer and runs (1) and (2) of strand *a*, and thus feeds strand *a* forwardly at the desired speed.

In the above explanation, and in FIG. 2, the flyer 24, and the capstan roll 45 are described as turning clockwise when viewed from below, and the runs (1) and (2) of strand *a* as initially engaging, and as leaving, respectively, the portion of the periphery 48 of the capstan roll 45 which is remote from the reader in FIG. 2. It is to be understood, however, that, if desired, the same strand feeding effect may be obtained if the flyer 24 and the capstan roll 45 rotate in a counterclockwise direction when viewed from below, the capstan roll rotates in the same direction as but at a lower speed than the flyer, and the runs (1) and (2) of strand *a* initially engage and leave, respectively, the portion of the periphery of the capstan roll 45 which faces the reader in FIG. 2.

In the illustrative embodiment, the hollow shaft or spindle 36, and thus the capstan roll 45 affixed thereto, are rotated in the same direction as, but slightly more slowly than, the flyer 24 by gear means, to be described, the driving effort being derived from the balloon, which, as we have seen, drives the auxiliary flyer 24. Because the upper end of spindle 36 is disposed outwardly of, here above, the flyer, however, the driving of the capstan roll 45 may be effected in other ways than by the gear train shown. Thus, for example, the spindle 36 could be driven by the same prime mover which drives the main spindle 14 of the apparatus, as through a suitable shaft or shafts and a "timing belt" drive connects between the terminal shaft and the upper, exposed end of spindle 36. Also, instead of the spur gear train shown, there may be employed suitable planetary, differential, or other suitable known speed reducing mechanisms.

The above-referred-to gear train extending between the flyer 24 and the capstan roll 45 is made up of the spindle 36 to which roll 45 is affixed and serially meshing gears 51, 52, 56, and 57. Gear 51 is affixed to the flyer 40 and gear 57 is affixed to the spindle 36. Such gear train causes the flyer 24 to drive the spindle 36 and capstan roll 45 in the same direction as and in synchronism with the flyer, but at a speed which is slightly less than that of the flyer, whereby the capstan roll 45 feeds the strand *a* forwardly, in the manner above explained.

The first gear 51 is a hollow pinion which is integral with part 42 of the flyer, and extends upwardly from such part 42 coaxially thereof. The spindle 36 extends through the axial passage in pinion 51 and is free to rotate relative to such pinion. Pinion 51 meshes with a second gear or pinion 52 which is mounted on a stub shaft 54 projecting upwardly from the fixed support 25. Shaft 54 is shown journaled in a bearing 55 in support 25. Removably secured to pinion 52 by conventional means (not shown), coaxially thereof and so as to turn therewith, is a third gear 56 which, in turn, meshes with the fourth gear or pinion 57. Pinion 57, in the illustrative embodiment, is removably secured to the spindle 36 by means of keys or lands (not specifically shown) on the inner wall of the central bore through the pinion, such keys being received in longitudinally extending grooves 59 in the outer surface 60 of the upper end of spindle 36. The gear 57 is

securely retained upon the spindle 36 by a nut 61 which is screwed onto the upper end of the spindle. The speed ratio of the drive through the above-described gear train may readily be changed as required by substituting other meshing gear sets of different pitch diameter ratios for the gears 56 and 57.

The ratio of the speeds of rotation of the flyer and the capstan roll 45, of course, will depend upon a number of factors, including the effective diameter of the surface 48 of roll 45, and the number of twists per inch of the two singles strands *a* and *b* about each other in the plied strand or cord produced by the apparatus. Let it be assumed, by way of example only, that the cord is to have 12 twists per inch, and that each 100 inches of cord contains 114 inches of each of singles strands *a* and *b*, the difference in such values being the amount of decrease in the effective length of the singles strands resulting from the twisting of the strands about each other. Knowing such parameters of a given ply-wrapping operation, the required speed reduction of the gear train from the flyer 24 to the capstan roll 45 for each permissible effective diameter of capstan roll 45 may readily be calculated. The final result will, of course, include as corrective factors the experimentally determined very small but inevitable creep of strand *a* upon the surface, and the similar small creep of the cord *c* upon the surfaces of the rolls of the cord take-up capstan 26.

In one illustrative, non-limiting example, the surface 48 of the capstan 45 has an effective circumference of about 2 inches. The plied strand or cord has the above assumed 12 twists per inch, and each 100 inches of cord contains 114 inches of each of singles strands *a* and *b*. To produce such 100 inches of cord the apparatus must rotate the loop or balloon 1,200 times, and the capstan roll 45, if the effective diameter of its surface 48 were exactly 2 inches, must rotate $114/2=57$ times in the strand feeding direction. The difference in the numbers of revolutions of the flyer and the capstan roll is $1,200-57=1,143$. The ratio of the speed reduction through the gear train between the flyer and the capstan is thus $1,200/1,143$. This is approximately $1.05/1$ or $21/20$. The latter ratio is readily attainable by an appropriate choice of the gears 51, 52 and 56, 57. Minor adjustments in the speed of feeding of the strand *a* by capstan roll 45 can readily be made by grinding the surface 48 of the capstan roll 45 down to the actual required diameter. It may be desired, for economy as well as flexibility of use of the apparatus, to make the capstan roll 45 removable from the spindle 36, and to connect it thereto by means similar to that employed herein for connecting the gear 57 to the spindle 36. This not only facilitates the machining of the capstan roll, but also permits the plying apparatus to be altered to produce cords with different twist characteristics by appropriate changes of the capstan roll and the gear train driving such capstan roll relative to the speed of rotation of the main spindle shaft 14 and the rate at which the cord is taken up by the capstan 26.

It will be apparent from the above that the illustrated strand handling method and apparatus of the invention may be altered considerably within the scope of the invention. The diameter of the strand engaging surface 48 of the capstan roll 45 may be varied appreciably consistent with the best modes of handling a particular strand *a*; also, the surface 48 of the capstan roll 45 may be cylindrical rather than dished, as shown, and the guides 47 and 49 on the flyer body 40 may be further vertically displaced so that successive wraps of the strand *a* on such cylindrical surface of the capstan roll will lie axially spaced from each other and at an appreciable helix angle relative to the axis of the capstan. Further, instead of disposing the guide 50 near the body 40 of the flyer 24, and causing the strand *a* to travel radially inwardly and upwardly to the plying or cording point *P*, such guide may be disposed at or adjacent the axis of the loop by supporting it on one or more rod-like members extending radially

inwardly from the body of the flyer. The inner strand *b* may then also be passed through the centrally located guide 50, along with strand *a*, the strands *a* and *b* then meeting and being wrapped around each other at a "plying point" which in reality is a zone of some length in which the strands are plied while travelling generally parallel to each other.

It should be pointed out that no twisting of the strand *a* takes place in its passage from its source of supply to the plying point, despite the continuance of its rotating loop from the loop proper around the capstan roll 45, through the run 2 of the strand, and through guides 49 and 50. Thus the feeding of the strand *a* in accordance with the present invention does not alter the essential characteristic of the illustrated skip twister of not altering the twist of the singles strands, as supplied to the apparatus, in forming a plied strand or cord therefrom.

If the strand *a*, after passing guide 50, were presented to a take-up bobbin mounted on a fixed support within the rotatable loop or balloon, however, rather than being turned to pass to the plying point and then out of the plying apparatus, the strand *a* would be subjected to two twists per revolution of the main spindle shaft 14. It can thus be seen that the strand feeding method and apparatus of the invention may also be employed to feed a strand to the take-up bobbin of a two-for-one downtwister. Because of the accessibility of the outer end of the spindle 36 or shaft upon which the capstan roll 45 is mounted, the speed of rotation of such capstan roll may readily be changed, if desired, during the operation of the apparatus by the use of a controllable change speed gearing device drivingly connected to the outer end of the spindle 36 instead of the gear train here shown which maintains a fixed difference between the speed of rotation of the loop or balloon generating flyer and the speed of rotation of the capstan roll 45.

The strand feeding method and apparatus of the invention have been illustrated herein in connection with their use in a cord forming apparatus of the uptwister ply-wrapping type, such apparatus employing an auxiliary flyer with which the capstan roll is associated. It will be understood, however, that the strand feeding method and apparatus of the invention may also be employed with a ply-wrapping cord former of the downtwister type wherein the outer ballooned strand travels inwardly through a balloon apex guide and after having passed through the rotating loop or balloon engages the balloon generating flyer. Such method and apparatus may also be employed in various other types of strand twisting apparatus wherein it is desired to feed a strand at a predetermined speed from or to a rotating loop or balloon. As will appear hereinafter, the direction of feeding of the strand by the apparatus of the invention is reversible.

One skip plying spindle of the downtwister type in accordance with the invention has the singles feeding capstan, and the gearing which drives it at constant speed from the main hollow shaft of the spindle, disposed, in that order, between the flyer and the stationary support for the supply package for the inner, non-balloonized strand. The outer ballooned singles strand is pulled inwardly by the capstan from the balloon or loop proper through a first guide affixed to the flyer. From the capstan, which is in the form of a capstan roll telescoped about and rotating with respect to the main shaft of the spindle, the thus fed outer singles strand travels radially outwardly to a second strand guide affixed to the flyer, and thence axially away from the gearing and the capstan and radially inwardly to enter an opening through the wall of the main spindle shaft, so as to meet and be plied with the inner strand as the latter travels through such shaft. As in the illustrated embodiment, the inner strand is subjected to a constant tension in advance of the plying point or zone. The thus plied strand or cord is taken up under tension, preferably at a constant speed somewhat slower than but suitably

related to that of the singles strand feeding capstan, as in the first illustrated embodiment.

In the embodiment now being described, the spindle is tipped at a pronounced angle to the vertical, the inner package support being eccentrically weighted to maintain it from rotation. Such eccentrically weighted support is, in this instance, employed as the stationary element upon which the two radially outer gears, corresponding to the gears 52 and 56 of the illustrated embodiment, are journaled. The gears may be mounted upon the heavier side of the package support, thereby desirably adding to the eccentric weighting of such support. As in the illustrated embodiment, the two radially outer gears of the gear train mesh, respectively, with a pinion fixedly connected to the flyer (in this instance being affixed to the main shaft of the spindle) and a pinion fixedly connected to the singles feeding capstan.

The last described, down-twister type strand plying spindle is compact, rugged, and is easily balanced dynamically for operation at high speeds. Very little, if any, weight need be added to the flyer per se in providing the first and second guides thereon, since by appropriate shaping of the flyer, as by making it of a shallow saucer shape with a depressed central well, both guides may be in the form of passages through the flyer body leading the singles strand to and away from the capstan roll. The singles feeding capstan and its drive train are mounted on the main spindle shaft and the stationary package support.

The action of the singles feeding capstan roll 45 per se is, as pointed out above, reversible as to the direction of flow of the strand engaged and fed thereby. Such reversal may be effected either by changing the direction of wrap of the strand about the capstan roll or by changing the algebraic sign of the difference in strand feeding effects between that caused by rotation of the flyer and that caused by rotation of the capstan roll. With twisting spindles handling only one strand, such as two-for-one twisters, the capstan may be employed to feed such strand either into or out of the loop or balloon. As a corollary, the flyer which cooperates with the capstan roll 45 may be driven by the balloon to rotate therewith, as here shown, or may be driven by a prime mover and function as a balloon-generating flyer.

Although a limited number of embodiments of the invention have been illustrated in the accompanying drawings and described in the foregoing specification, it is to be especially understood that various changes, such as in the relative dimensions of the parts, materials used, and the like, as well as the suggested manner of use of the apparatus of the invention, may be made therein without departing from the spirit and scope of the invention, as will now be apparent to those skilled in the art.

What is claimed is:

1. A method of handling a strand travelling through a loop rotating at a predetermined speed about its axis, which comprises disposing a capstan roll coaxial of the loop, extending the strand from one end of the main portion of the loop in a first run extending through a first guide disposed radially outwardly of the axis of the loop and thence to the capstan roll, wrapping the strand in substantially non-slipping engagement about the capstan roll, disposing a further portion of the strand extending from and beyond the capstan roll in a second run passing through a second guide disposed radially outwardly of the axis of the loop, rotating the two guides together in the same direction and at the same speed as the rotating loop in such direction relative to the direction of winding of the strand on the capstan roll that if the capstan roll were held from rotation a desired one of the runs of the strand would be wrapped upon and the other run of the strand would be unwrapped from the capstan roll whereby the strand would then be fed in the desired direction, and rotating the capstan roll at a speed which is different in a predetermined amount from the speed of rotation of the loop and the guides, the cap-

stan roll feeding the strand therepast at a controlled predetermined speed which is proportional to the resultant of the strand feeding effect of the joint rotation of the loop and the guides and the strand feeding effect of the rotation of the capstan roll.

2. A method as claimed in claim 1, wherein the capstan roll delivers the strand at constant speed, and wherein the loop and the capstan roll rotate at speeds the ratio of which is constant.

3. A method as claimed in claim 2, wherein the first guide is disposed substantially at one end of the loop proper, the capstan roll is disposed adjacent the same end of the loop, and the first run of the strand extends substantially directly from the first guide to the capstan and lays the strand on the capstan roll.

4. A method as claimed in claim 3, wherein the second guide is disposed adjacent said one end of the loop proper, the second run of the strand extends substantially directly from the capstan roll to the second guide, and the second guide removes the strand from the capstan roll.

5. A method as claimed in claim 1, wherein the loop and capstan roll rotate at constant speeds, and comprising driving the capstan roll in the same direction as the direction of rotation of the loop.

6. A method as claimed in claim 5, comprising driving the capstan roll at a speed which is lower than the speed of rotation of the loop.

7. A method as claimed in claim 5, comprising driving the capstan roll at a speed which is higher than the speed of rotation of the loop.

8. A method as claimed in claim 2, wherein the capstan roll feeds the strand from the loop into the space within the loop, and comprising taking up the strand after it has left the second guide.

9. A method as claimed in claim 1, wherein the capstan roll has an at least generally axially extending passage therethrough, and comprising passing the strand after it leaves the second guide outwardly of the loop along a path extending through the said passage through the capstan roll.

10. A method as claimed in claim 9, comprising disposing a source of supply of a second strand within the loop, feeding the second strand from said source toward the passage through the capstan roll so that the two strands engage and twist about each other at a plying point, withdrawing the two strands together through the passage in the capstan roll, and taking up the plied strand outwardly of the loop.

11. Apparatus for feeding at a controlled speed a strand travelling through a loop rotating at a predetermined speed about its axis, which comprises a capstan roll disposed coaxial of the loop, means mounting the capstan roll for rotation about its axis, means including a first guide disposed radially outwardly of the axis of the loop for extending the strand from one end of the main portion of the loop in a first run extending through said first guide and thence to the capstan roll, the capstan roll being adapted to receive the strand wrapped thereabout in substantially non-slipping engagement therewith, means including a second guide disposed radially outwardly of the axis of the loop for extending a further portion of the strand from and beyond the capstan roll in a second run passing through said second guide, means for rotat-

ing the two guides together in the same direction and at the same speed as the rotating loop in such direction relative to the direction of winding of the strand on the capstan roll that if the capstan roll were held from rotation a desired one of the runs of the strand would be wrapped upon and the other run of the strand would be unwrapped from the capstan roll whereby the strand would then be fed in the desired direction, and means for rotating the capstan roll at a speed which is different in a predetermined amount from the speed of rotation of the loop and the guides, whereby the capstan roll feeds the strand therepast at a controlled predetermined speed which is proportional to the resultant of the strand feeding effect of the joint rotation of the loop and the guides and the strand feeding effect of the rotation of the capstan roll.

12. Apparatus as claimed in claim 11, wherein the means for rotating the capstan roll at a speed which is different in a predetermined amount from the speed of rotation of the loop and the guides comprises means for maintaining constant the ratio of the speed of rotation of the loop and the capstan roll.

13. Apparatus as claimed in claim 12, wherein the first and second guides are disposed substantially at one end of the loop proper, the capstan roll is disposed adjacent the same end of the loop, the first run of the strand extends substantially directly from the first guide to the capstan and lays the strand on the capstan roll, the second run of the strand extends substantially directly from the capstan roll to the second guide, and the second guide removes the strand from the capstan roll.

14. Apparatus as claimed in claim 13, wherein the capstan roll has an at least generally axially extending passage therethrough, and comprising means for passing the strand after it leaves the second guide outwardly of the loop along a path extending through the said passage through said capstan roll, and means for taking up the strand outwardly of the loop after it has passed through the capstan roll.

15. Apparatus as claimed in claim 14, comprising a source of supply of a second strand within the loop, means for feeding the second strand under tension from said source toward the passage through the capstan roll so that the two strands engage and are plied at a plying point, and wherein said means for taking up the first recited strand outwardly of the loop takes up under tension the plied strand formed of the first recited and second strands.

16. Apparatus as claimed in claim 15, comprising means for rotating the loop at constant speed.
